UNITED STATES PATENT OFFICE

109,784

DESIGN FOR A VEHICLE BODY OR SIMILAR ARTICLE

Paul P. Cret and John W. Patton, Philadelphia, Pa., assignors to Edward G. Budd Manufacturing Company, Philadelphia, Pa., a corporation of Pennsylvania

Application May 28, 1937, Serial No. 69,596

Term of patent 14 years

To all whom it may concern:

Be it known that we, Paul P. Cret and John W. Patton, citizens of the United States, residing at Philadelphia, in the county of Philadelphia and State of Pennsylvania, have invented a new, original, and ornamental Design for a Vehicle Body or Similar Article, of which the following is a specification, reference being had to the accompanying drawings which form a part thereof.

Fig. 1 is a horizontal section taken substantially in the plane of the port lights, of a vehicle body, the interior of which embodies the design.

Fig. 2 is a vertical section through the vehicle body shown in Fig. 1, taken on line 2—2 of Fig. 1 and viewed in the direction of the arrows.

Fig. 3 is a perspective view taken on line 3—3 of Fig. 1 looking toward the interior of the vehicle body.

Fig. 4 is a perspective view of a conventional vehicle body, the interior of which embodies the design.

The design is characterized by the interior portion of the vehicle body, especially as shown in Figs. 1 and 2.

We claim:

The ornamental design for a vehicle body or similar article, substantially as shown and described.

PAUL P. CRET.
JOHN W. PATTON.
